UNITED STATES PATENT OFFICE.

JERRY L. STAIR, OF CHICAGO, ILLINOIS.

DESIGN FOR A COVE REFLECTOR.

Application filed June 2, 1922. Serial No. 2,506. Term of patent $3\frac{1}{2}$ years.

To all whom it may concern:

Be it known that I, JERRY L. STAIR, a citizen of the United States, residing at Chicago, in the county of Cook and State of Illinois, have invented a new, original, and ornamental Design for Cove Reflectors, of which the following is a specification, reference being had to the accompanying drawing, forming a part thereof.

In the drawings—

Fig. 1 is a front view of a cove reflector showing my new design;

Fig. 2 is a top plan view thereof; and

Fig. 3 is an end view of the same.

I claim:

The ornamental design for a cove reflector, as shown.

JERRY L. STAIR.
